UNITED STATES PATENT OFFICE

KATE V. WATERHOUSE, OF DETROIT, MICHIGAN.

DESIGN FOR A CORN-FORK.

43,345.

Specification for Design.

Patented Dec. 10, 1912.

Application filed October 7, 1912. Serial No. 724,453. Term of patent 14 years.

To all whom it may concern:

Be it known that I, KATE V. WATERHOUSE, a citizen of the United States, residing at Detroit, in the county of Wayne and State of Michigan, have invented a new, original, and ornamental Design for Corn-Forks, of which the following is a specification, reference being had to the accompanying drawing, forming part thereof.

Figure 1 is a plan view of a corn fork

showing my new design applied thereto. Fig. 2 is a side or edge view of the same.

I claim:

The ornamental design for a corn fork as shown.

KATE V. WATERHOUSE.

Witnesses:

EDWIN HERZOG,
T. E. NEWKIRK.
